CLAIM

The ornamental design for a toy water gun, as shown and described.

DESCRIPTION

The file of this patent contains at least one drawing/photograph executed in color. Copies of this patent with color drawings/photographs will be provided by the Office upon request and payment of the necessary fee.

FIG. 1 is a top, front and right side perspective view of a toy water gun showing my new design;

FIG. 2 is a top, rear and left side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is another perspective view showing the toy water gun with its mouth open; and,

FIG. 10 is another bottom plan view showing the toy water gun with its trigger pulled.

The color shown on the claimed design forms no part thereof.
